UNITED STATES PATENT OFFICE.

JACQUES KELLERMANN, OF BERLIN, GERMANY.

PYROPHOROUS GAS-LIGHTER.

1,099,447.

Specification of Letters Patent.

Patented June 9, 1914.

Application filed October 28, 1913. Serial No. 797,771.

To all whom it may concern:

Be it known that I, JACQUES KELLERMANN, a subject of the German Emperor, and residing at 114 Köpenickerstrasse, Berlin, S. O. 5 16, Germany, have invented certain new and useful Improvements in Pyrophorous Gas-Lighters, of which the following is a specification.

The present invention consists of a pyrophorous gas-lighter with means for fixing it, which are so constructed, that the gas lighter may be fitted by any one to gas lamps, without the need of any special tools or other contrivances.

15 The gas-lighter further comprises a wall covering the sparks produced by the pyrophorous material, which wall will conduct the sparks over the upper edge of the gas lamp to be lighted, so that the said sparks 20 will positively meet the gas rising from the lamp, and ignite it.

The gas lighter is operated by means of a rocking lever under action of a spring, by the rocking of which the frictional member is operated, whereby the spark is produced.

In the accompanying drawing Figure 1 is a gas lamp which is fitted with the pyrophorous gas-lighter. Figs. 2 and 3 are 30 broken side views of the gas-lighter in two different positions and Fig. 4 is a cross section on the line IV—IV of Fig. 2. Figs. 5 and 6 illustrate a modification of the arrangement shown in Figs. 2 and 3.

35 The gas lighter consists of a casing 1, which has at its upper edge a hook-shaped nose 2. Another hook 4 is attached to a spring 3 secured at one end to the said casing 1, and by means of these two hooks the casing can 40 be attached to the gas lamp. In the embodiment shown in the accompanying drawing the gas-lighter is shown fitted to an inverted gas lamp, the hook 2 engaging over the top rim 5 of the burner casing, while 45 the hook 4 at the free end of the spring engages over the lower rim or in one of the perforations which are generally found in such burners. By means of the tension of the spring 3 between the said two hooks the 50 gas-lighter can readily and without any further instruments be attached to any such gas lamp. The casing 1 is further preferably provided below with an extension 6, which serves as a kind of support, bearing 55 against the body of the lamp. On the top

of the casing is a small tube 7 or any other suitable device for receiving the pyrophorous metal 8, which is frictioned for producing the sparks by means of a file 10 moving in a guide 9. This file 10 is under action 60 of a spring 11 (Fig. 3) which tends to move the file in the direction indicated by the arrow II (Fig. 3) into the position shown in Fig. 2. For operating this file 10 a rocking lever 12 is provided, which is under action 65 of a spring 13, which tends to return the lever into its upper position, when it has been moved downward in the direction of the arrow I (Fig. 1). A nose 14 of the lever 12 engages behind a pawl 15 on the file 10. 70 When, therefore, the lever 12 is rocked the file will be moved by means of the nose 14 and the pawl 15, as shown in Fig. 3, until the nose 14 is disengaged from the pawl 15, and the latter is released, whereupon the file 75 10 can swing back in the direction of arrow II, Fig. 3. When the lever 12 is again released its nose 14 will strike against the pawl 15, which is under action of a spring 16 and is thereby swung back, so that the nose 80 14 can pass whereupon it reengages behind the returning pawl 15 as shown in Fig. 2.

In order to positively conduct the sparks into the path of the ignitable gas current rising from the lamp, a wall 16 is provided 85 above the hook 2, by which wall the sparks produced by the file are made to pass over the upper edge 5 of the gas lamp. At the same time this wall 16 will catch a part of the rising gas and conduct it toward the 90 sparks. The wall 16 thus together with the guide 9 and the file 10 forms a guide passage for the sparks.

In Figs. 5 and 6 the pawl 15 in Figs. 2 and 3 has been replaced by a lug 18 eccentrically 95 bored and pivoted at 17. This lug 18 has such a shape, that it, and with it the file 10, is dogged by lever 12, and after clearing the lever 12 it returns and allows the arm 14 to pass, thereupon returning by its own 100 weight into its position of rest. By this arrangement the auxiliary spring of pawl 15 in Figs. 2 and 3 is dispensed with and a reliable operation of the device is insured.

I claim:

1. In a pyrophorous gas lighter means for readily attaching it to a lamp and detaching it therefrom, said means consisting of a hook fitted to the body of the lighter and adapted to engage over the top rim of the 110

105

lamp, a second hook adapted to engage below with the lamp, and an elastic member between said hooks.

2. In a pyrophorous gas lighter means for readily attaching it to a lamp and detaching it therefrom, said means consisting of a hook fitted to the body of the lighter and adapted to engage over the top rim of the lamp, a second hook adapted to engage below with the lamp, and an elastic member between said hooks, on said body of the lighter and at its lower end a bracket adapted to bear against the body of the lamp and act as a support for the lighter.
- 15 3. In a pyrophorous gas lighter means for readily attaching it to a lamp and detaching it therefrom, said means consisting of a hook fitted to the body of the lighter and adapted to engage over the top rim of the lamp, a second hook adapted to engage below with the lamp and an elastic member between said hooks, over the said upper hook a wall projecting beyond it and adapted to act as a baffle for the sparks and conduct them into the current of gas rising and also
- 20 25

to baffle the said rising current of gas toward the sparks.

4. In a pyrophorous gas lighter means for readily attaching it to the lamp and detaching it therefrom, said means consisting of a hook fitted to the body of the lighter and adapted to engage over the top rim of the lamp, a second hook adapted to engage below with the lamp and an elastic member between said hooks, clamping them to the lamp, over the said upper hook a wall projecting beyond it and adapted to act as a baffle for the sparks and conduct them into the current of gas rising and also to baffle the said rising current of gas, a friction member moving in a guide arranged beneath and in the direction of the said baffling wall and forming with said wall a guide channel for the sparks.

In testimony whereof I hereunto set my hand in the presence of two witnesses.

JACQUES KELLERMANN.
